United States Patent Office.

JAMES W. HANKENSON, OF MINNEAPOLIS, MINNESOTA, ASSIGNOR TO HIMSELF AND WINSLOW BAKER, OF SAME PLACE.

Letters Patent No. 99,184, dated January 25, 1870.

IMPROVEMENT IN LIGHTNING-RODS AND CONDUCTORS.

The Schedule referred to in these Letters Patent and making part of the same.

To all whom it may concern:

Be it known that I, JAMES W. HANKENSON, of Minneapolis, in the county of Hennepin, and State of Minnesota, have invented certain new and useful Improvements in Lightning-Conductors; and I do hereby declare that the following is a full and exact description of the same, reference being had to the accompanying drawings, and letters of reference marked thereon, which make a part of this specification.

The design of my invention is to introduce improvements in copper-strip conductors, by giving the flat strip such new and improved shape as shall increase its strength and durability, and also provide for its insulation from the building, thus increasing its efficiency as an electrical conductor, and also preventing the corrosion and stain caused by water dripping down the side of a building, with which the strip is in immediate contact.

To enable others skilled in the art to make and use my invention, I will describe its construction and operation.

A represents a strip of copper, fashioned into a semi-tubular shape, with its edges rimmed out in the form of a square flange, thus giving it such strength and stiffness as will allow the use of bracket-attachments for its support, instead of placing the strip flat against the surface of the building, the strip being cut into sections of any desired length. Near one end of each piece or section are cut two small slots *b b*, while near the opposite end are small tongues *c c*, which are inserted through the slots of the adjacent section, and

clasped upon the inside, in this manner jointing together two sections, as shown at B.

C represent non-conducting attachments, fastened to the building at convenient distances, by which the jointed strip is supported. These attachments are strips of zinc, made in the form of a bracket, with its face moulded or curved into a shape which corresponds with that of the copper strip, as above described. Across each attachment are cut two parallel and horizontal slots *e e*, through which is passed the copper strip, which, being thus insulated, is in like manner firmly supported at a safe and uniform distance from the building.

In putting on these attachments, a margin is left at each end of the zinc strip, sufficient to be turned and hammered over, so as to completely cover any nails or metallic fastenings.

What I claim as my invention, and desire to secure by Letters Patent, is—

1. The lightning-conductor A, when composed of a series of copper strips, made in semi-tubular form, with flange-like edges, and jointed together by slots and tongues, substantially as shown and described.

2. In combination with conductor A, the zinc attachment C, with face curved to correspond with the shape of the conductor, and having two slots, through which the conductor is passed, and thereby secured, substantially as described.

Witnesses: JAMES W. HANKENSON.

E. S. JONES,

Wm. CHENEY.
